REFRIGERATOR EVAPORATOR

Filed May 21, 1926

Inventor
Charles L. Heisler,
by *Charles L. Heisler*
His Attorney.

UNITED STATES PATENT OFFICE.

CHARLES L. HEISLER, OF SCHENECTADY, NEW YORK, ASSIGNOR TO GENERAL ELECTRIC COMPANY, A CORPORATION OF NEW YORK.

REFRIGERATOR EVAPORATOR.

Application filed May 21, 1926. Serial No. 110,647.

My invention relates to refrigerating apparatus and particularly to an evaporator or boiler in which a liquid refrigerant is vaporized by the absorption of heat from the surrounding medium. An object of my invention is the provision of an improved evaporator whose construction is compact and durable, which is efficient in operation and which may be manufactured at a relatively low cost. 10 My invention will be better understood from the following description taken in connection with the accompanying drawing, and its scope will be pointed out in the appended claims.

15 Referring to the drawing, Fig. 1 is a perspective view of an evaporator embodying my invention with parts broken away to more clearly illustrate the construction; Fig. 2 is a detail; Figs. 3, 4 and 5 are side views of modified forms; and Fig. 6 illustrates by way of example the evaporator comprising my invention installed in a refrigerator.

In Fig. 1 of the drawing the evaporator is shown comprising a header 1 and two shelf-like members 2 and 3. These members each comprise a pair of sheet metal plates, an upper and a lower plate, spaced from each other to form a refrigerant container and firmly secured at their edges to spacing strips 4. 25 Between the plates are spacing ribs 5 arranged at intervals across the plates and extending lengthwise thereof. The plates are tightly secured at one end to the header 1, as for example by welding, and the space between the plates of each pair is in direct communication with the interior of the header. 30 In order that the refrigerant may freely circulate between the header and the several passages formed by the plates and ribs the ribs are preferably discontinued at the ends of the shelves adjacent the header.

In Fig. 1 the plates of one shelf are shown continuous with those of the next shelf, that is, the top plate of upper shelf 2 is continuous with the bottom plate of lower shelf 3 and the bottom plate of upper shelf 2 is continuous with the top plate of lower shelf 3. This construction may expeditiously be fashioned by first securing the plates of the two shelves to the marginal spacing strips 4 and ribs 5 and then bending the structure thus formed double. The evaporator thus formed provides for the free circulation of the refrigerant therein through the shelves in series. In 45 the modification illustrated in Fig. 4, the two

shelves 2 and 3 are shown connected together by nipples 7, thereby also permitting the free circulation of the refrigerant. Where a greater number of shelves is desired they obviously may be connected together by suitably arranged nipples 7 or if the continuous type of construction shown in Fig. 1 is desired the several shelves may be formed by bending back and forth the previously built-up plate structure 8 so as to circulate the refrigerant 60 therethrough in series, as shown for example in Fig. 5, the structure being in communication with the header only at its two ends although it may be anchored to the header if desired at an intermediate portion as at 9. 65

By forming the evaporator with substantially horizontal shelf-like portions containing liquid refrigerant the cooling of material which is adapted to be placed on the shelves and particularly when the material can be placed between two adjacent shelves 75 is greatly facilitated. I have shown for example in Figs. 3 and 5 an evaporator each of whose shelves support two trays 10 such as are commonly used for freezing ice cubes. 80 It will be noted that in the case of the trays resting on any but the upper shelf heat is withdrawn from the trays from both below and above, the trays being substantially surrounded by portions of the evaporator. 85 Freezing of ice cubes in these trays is thereby made possible in only a fraction of the time heretofore required.

Liquid refrigerant may be supplied to the evaporator by the pipe 12 and the flow of refrigerant may be controlled by the valve 13 which is actuated by the lever 14 pivoted to the float 15. The valve, lever, and float are all arranged within the header 1, the float being constructed to open the valve when the liquid refrigerant level falls below a predetermined point. Vaporized refrigerant is withdrawn from the header through pipe 17. The header 1 serves also as a separator for the lubricating oil carried along with the liquid refrigerant, the header being provided with a dome 18 in which the oil collects as indicated at 19 in Fig. 3. The pipe 17 by which the vaporized refrigerant is withdrawn also carries away the oil and in order to limit the flow of oil to the compressor when the same is started after a period of idleness during which a considerable quantity of oil may collect, the upper end of pipe 17 is provided with a slot 20 which runs down approximately to 105 110

the point at which it is desired to maintain the level of the oil in the header. This arrangement of the outlet pipe forms no part of my invention, and is described and claimed 5 in the application of C. Steenstrup, Serial No. 109,960, filed May 18, 1926, which is assigned to the same assignee as the present application.

For the purpose of catching the drip from 10 the evaporator when it is defrosted I have provided a tray 22 which is shown secured to the bottom plate 23 of the header and to which is connected the drip pipe 24 which may lead off to a suitable receptacle or to a sewer. The 15 bottom plate 23 is shown in Fig. 2, having a groove 25 on its under surface by which the drip is led to the mouth of the tube 24. The shelves are shown having a slight inclination whereby the drip will flow to a position where 20 it will be caught by the drip tray. In Fig. 20 I have shown by way of illustration only an evaporator in accordance with my invention arranged in a refrigerator box 26 in the base of which is located the mechanism 27 to 25 which lead pipes 12 and 17 and by which the vaporized refrigerant is compressed and liquefied. Pipes 12, 17 and 24 are shown enclosed by a tubular casing 28 where they pass through the refrigerator box. Obviously the 30 mechanism 27 may be arranged at a point remote from the refrigerator box if desired.

What I claim as new and desire to secure by Letters Patent of the United States, is.—

1. A refrigerator evaporator comprising a plurality of refrigerant containing shelves 35 arranged one above the other and adapted to support material to be cooled, means for connecting said shelves to provide for circulation of the refrigerant therethrough in series, and means for supplying liquid refrigerant thereto and for withdrawing vaporized refrigerant therefrom.

2. A refrigerator evaporator comprising a plurality of pairs of spaced plates, the pairs 45 of plates being connected with each other at one portion thereof and a header connected therewith at another portion thereof.

3. A refrigerator evaporator comprising a pair of spaced plates forming a refrigerant 50 containing receptacle, a similar pair of spaced plates arranged below the first pair of plates and forming a receptacle adapted to support material to be cooled, and means for connecting the receptacles together to provide for circulation of the refrigerant therethrough in series.

4. A refrigerator evaporator comprising

pairs of spaced plates, the pairs of plates being arranged one above the other to form shelves adapted to support material to be 60 cooled, said pairs of plates being connected together at one end, and a header connecting the pairs of plates together at the other end.

5. A refrigerator evaporator comprising a plurality of superposed pairs of spaced 65 plates having terminal portions connected together to form a series path for the circulation of refrigerant adapted to be contained therein, and a header connected therewith at points corresponding to the ends of said series 70 path.

6. A refrigerator evaporator comprising refrigerant containing shelves, a header connecting said shelves forming a float chamber, a valve for admitting liquid refrigerant to 75 the evaporator, and a float for controlling said valve arranged in said float chambers.

7. A refrigerator evaporator comprising a header, a plurality of shelf-like members connected thereto, a drip pan secured to the header beneath the shelf-like members and means for withdrawing water collected by 80 said drip pan.

8. In a mechanical refrigerating system, a U-shaped refrigerant expander unit including 85 a container for refrigerant comprising sheet metal plates spaced apart and affording a chamber therebetween, to thus form said container, the legs of said U-shaped expander being spaced to receive an ice tray 90 therebetween supported on the top surface of the lower leg of said expander when said legs extend horizontally one above the other.

9. In a mechanical refrigerating system, a refrigerant expander unit including two sheet 95 metal plates spaced apart and bent to form a container of substantially U-shape, the legs of said container being spaced to form a tray receiving recess therebetween, and spacing means intermediate the peripheral edges of 100 said plates within said container.

10. In a mechanical refrigerating system, a refrigerant expander unit including two sheet metal plates spaced apart and bent to form a container of substantially U-shape, the legs 105 of said container being spaced to form a tray receiving recess therebetween, spacing means intermediate the peripheral edges of said plates within said container, and means associated with said container for connection 110 with a refrigerant circuit.

In witness whereof, I have hereunto set my hand this 17th day of May, 1926.

CHARLES L. HEISLER.
